No. 36,980.

Patented June 14, 1904.

UNITED STATES PATENT OFFICE.

ROBERT ZEDLER, OF NEW YORK, N. Y.

DESIGN FOR A PILLOW-SHAM OR SIMILAR ARTICLE.

SPECIFICATION forming part of Design No. 36,980, dated June 14, 1904.

Application filed May 7, 1904. Serial No. 206,962. Term of patent 7 years.

To all whom it may concern:

Be it known that I, ROBERT ZEDLER, a citizen of the United States, residing in the city of New York, borough of Manhattan, county and State of New York, have invented a new, original, and ornamental Design for Pillow-Shams or Similar Articles, of which the following is a specification.

My new design is represented in the accompanying drawing, forming a part hereof, wherein is shown a face view of a pillow-sham embodying my design.

What I claim is—

The ornamental design for a pillow-sham or similar article, as herein shown.

ROBERT ZEDLER.
